assignor to said Dibrell

Application August 26, 1948, Serial No. 46,288

8 Claims. (Cl. 33—30)

1

This invention relates to drawing instruments and more particularly to instruments of this kind adapted for the drawing of true ellipses by operations similar to those used for drawing circles with compasses.

A principal object of the invention is to provide an instrument of this character that will facilitate drafting work involving the drawing of ellipses by making it possible to draw any desired size and angle of view ellipse almost as readily and easily as a circle now can be drawn with an ordinary compass.

A feature of the invention is that it will make possible the drawing of generally perfect ellipses readily and without the use of templates. Thus, draftsmen and industrial design artists will have greater freedom in choosing perspective views because of the elimination of restrictions necessarily imposed by the use of ellipse templates, the standard method. In other words, it will be possible to fit the tools to the work rather than being forced to adapt the work to the available tools.

Another object of the invention is the provision of a mechanically simple device that will be fully effective for the purposes intended and that will be simple to operate and to adjust to render possible the drawing of ellipses of any desired size and angle of view.

Other objects, novel features of the invention will become apparent from the following description and the accompanying drawings, wherein:

Fig. 1 is an elevational view partially sectioned of a drawing instrument embodying the invention;

Fig. 2 is a side elevational view seen from the right of Fig. 1;

Fig. 3 is a top plan view of the instrument;

Fig. 4 is a fragmentary section taken along the line 4—4 of Fig. 1 and viewed in the direction of the arrows;

Fig. 5 is a longitudinal sectional view taken along the line 5—5 of Fig. 2 and also viewed in the direction of the arrows;

Fig. 6 is a sectional view taken along line 6—6 of Fig. 5;

Fig. 7 is an enlarged fragmentary elevational view of structural features included on a smaller scale in Fig. 1;

Fig. 8 is a fragmentary section taken along line 8—8 of Fig. 7; and

Fig. 9 is a sectional view taken in the plane of line 5—5 of Fig. 2 of one of the structural elements of the device.

In general, the invention consists of a mechanical means to generate a cylindroidal surface

(which is the limiting form of a convex surface of fixed base as its apex is moved to infinity) having an elliptical perpendicular cross-section, the major axis length of the elliptical cross-section being fixed, with means provided mechanically to adjust continuously as desired the minor axis length of the elliptical perpendicular cross-section and mechanical means to generate simultaneously with the cylindroidal surface a plane which cuts a perpendicular cross-section through the cylindroidal surface as it is generated, together with mechanical linkage to amplify this elliptical cross-section as desired and to project and draw it on a chosen plane surface which also is perpendicular to the axis of the generated cylindroidal surface.

Referring to the drawings, a central shaft or spindle 10 is provided. The vertical axis of this shaft 10 constitutes a fixed center of rotation 20 about which other operating parts of the device are adapted to be rotated for the purpose of generating and reproducing the ellipse of desired form and angular view as will presently be described.

25 A knob 11 is fixedly secured preferably to the upper end of the shaft 10 and this knob is adapted to be held firmly by the user of the device when the device is operated so as to prevent rotation of said shaft 10. Portions 12, 13 and 14 of 30 reduced diameter are provided in the length of the shaft 10 for purposes presently to be described. The lowermost reduced portion 14 appears at the lowermost end of the shaft 10. This reduced portion 14 is provided at its outermost end with a threaded socket 15 into which a centering pin 16 having a flange 16a is received. This pin 16 has a pointed end 17 which may be positioned at any desired location on a drawing surface 18 such as a sheet of paper or other drawing material on a drawing table 19.

A portion 20 of the shaft 10 intermediate the reduced portions 12 and 13 is flattened and substantially wider in its large dimension than the diameter of the main body of the shaft 10, defining the respective shoulders 21 and 22 therewith. A collar-like carrying member 25 is rotatively mounted on the shaft 10 and rests upon the shoulder 21. A manipulating rod 26 which threadedly engages the member 25 at 27 extends 50 radially outwardly of the member 25 and preferably at right angles to the axis of shaft 10 and is provided with a manipulating knob 28. A diametrical transversely extending bore or hole 30 is provided in the member 25 and is positioned 55 to lie in the region of the reduced portion 12

of the shaft 10. A guiding rod 31 is slidably guided in the hole 30 of member 25. This guiding rod 31 has a longitudinal slot into which the reduced portion 12 of the shaft 10 fits slidably so that the rod 31 is free to move longitudinally in the bore 30 and in radial directions of the shaft 10 at right angles to the axis of the latter. A sleeve 34 is threadedly engaged in an enlarged threaded opening 35 in member 25 concentric with the opening 30. A biasing spring 36 is carried within the sleeve 34 and surrounds the slotted portion of the rod 31. One end of the spring 36 engages the face of the member 25 adjacent the threaded opening 35 and its opposite end engages an annular flange 37 attached to the rod 31. Thus, as seen in Figs. 1 and 5, the spring 36 biases the rod 31 toward the right of said two figures for the purposes presently to be described. A suitable cover 38 is provided for the outer end of the sleeve 34.

A frame-like supporting part 40 is secured to the rod 31 at 41. The manipulating rod 26 extends through an opening 42 in the frame-like part 40 so that the latter may move freely along the length of said rod 26 in a horizontal direction toward and away from the longitudinal axis of the main shaft 10.

As seen in Figs. 1 and 5, the frame-like part 40 is substantially L-shaped in cross section and the vertical leg of the L has the opening 42 through which the manipulating rod 26 is moveable slidably and also has the securing means 41 for the rod 31.

A collar-like carrying member 45 is positioned on the shaft 10 with its upper edge in engagement with the shoulder 22. This member 45 is rotatively secured in this position, for example, by means of the split spring ring 46. This member 45 has a diametrical, transversely extending bore 47 in the region of the reduced portion 13 of the shaft 10. A guiding rod 48 is slidably mounted within the bore 47 for horizontal radial movement relative to the axis of the shaft 10. This rod 48 is slotted similarly to rod 31 and biased toward the right as seen in Figs. 1 and 5 by the biasing spring 49 carried within sleeve 50 secured to the member 45 in its threaded opening 51. The biasing action of spring 49 upon the guiding rod 48 is in the same direction as the biasing action of the spring 36 upon the guiding rod 31.

A supporting member 53 is secured at 54 to the guiding rod 48. A cam follower bar 56 extends transversely between the horizontal leg of the frame-like part 40 and the supporting member 53, its longitudinal axis extending in a direction which is substantially parallel to the direction of the longitudinal axis of the shaft 10. The bar 56 is secured respectively at 57 and 58 to the frame-like part 40 and to the supporting member 53. An extension bar 60 is secured at 61 to the supporting member 53 with its axis projecting parallel with the axis of the shaft 10 and below the cam follower bar 56. Because the bars 56 and 60 are secured respectively to the frame-like part 40 and member 53 and in turn are guided for horizontal movement by the respective guiding rods 31 and 48, the bars 56 and 60 are necessarily movable simultaneously only in radial directions toward and away from the axis of shaft 10 but also may be rotated as a unit about said main shaft axis as a center by manipulation of the knob 28 on rod 26. However, they are always maintained in parallelism with the axis of shaft 10 and this disposition may not be changed.

A collar-like carrying member 65 is rotatively

mounted on the shaft 10 adjacent the reduced portion 14 being held against removal therefrom by the flange 16a of the pin member 16 and against upward movement relative to the shaft 10 by the shoulder 66 and also by engagement of the lowermost end of the bar 60 in a horizontally extending groove 67 provided on the member 65. A horizontally extending bore 68 is provided in the member 65. This bore receives a longitudinal slideable guide member 69 which is provided with a longitudinal slot 70 in which the reduced portion 14 of the main shaft 10 engages slidably.

A scribe or marker support 72 is fixedly attached at 73 to the horizontally movable guide rod 69. A marking member socket 74 provided with a set screw 75 is secured to the member 72 and a marking device such as a pointed lead 76 or other type of scribe is removably supported in the socket 74. This socket 74 has a definite position relative to certain parts, as will be described.

The control mechanism for drawing ellipses comprises a circular ring 80, having substantially toroidal sections, which is supported for rotation about a diametrical axis that is transverse and at right angles to the axis of the shaft 10. As seen in Fig. 6, the outer surface 81 of the ring has substantially semi-circular contour while the inner surface 82 is substantially straight walled or flattened. The locus of centers generating the semi-circular contour is a circle lying in the central plane of the ring 80. This ring 80 is adapted to be supported from the main shaft 10 so that its center of generation, irrespective of the angular adjustment of the central plane of the ring 80 relative to the axis of the main shaft 10, always remains fixed and intersected by said axis.

To this end, in the embodiment shown, the ring 80 is provided at diametrically opposite points with threaded holes 83 and 84. Also, the widened and flattened portion 20 of the shaft 10 is provided with a transversely extending bore 85 having a widened portion 86. The axis of this bore intersects the axis of main shaft 10.

A stub shaft 88 threadedly engages the threaded bore 83 of the ring 80 and extends toward the diametrically opposite bore 84. A flange 88a is provided intermediate the ends of shaft 88 and the latter is threaded at 89 and extends through the bores 85, 86 of the shaft portion 20. An exteriorly knurled internally threaded collar 90 having a portion dimensioned to fit within the widened portion 86 of bore 85 threadedly engages portion 89 of the stub shaft 88. A stub shaft 91 threadedly engaging the threaded bore 84 in the ring 80 rotatively engages in the bore or socket of the knurled collar 90 so that the axes of the two stub shafts 88, 91 are aligned. The adjustable relationship of the stub shaft 88 relative to the ring 80 permits exact positioning of the center of generation of the ring 80 for intersection by the axis of the shaft 10. The knurling on the collar 90 permits loosening of the latter on the threaded portion 89 of stub shaft 88 sufficiently to permit an angular adjustment of the central plane of the ring 80, relative to the axis of main shaft 10, and tightening of the collar against portion 20 of shaft 10 thereafter acts to fix the adjusted position of said central plane of said ring 80.

The cam bar 56 is always biased into contact with the external curved surface 81 of the ring 80 by the action of the biasing springs 46 and 49 on the guide rods 31 and 49 irrespective of the an-

gular adjusted disposition of the ring 80 on its axis of adjustment, namely, the aligned axes of stub shafts 88 and 91.

Since it is desirable to permit angular adjustment of the central plane of the ring 80 into near parallelism with the axis of the shaft 10, or at least to within approximately 5° of parallelism therewith, clearance recesses 93 are provided in the ring 80 and corresponding clearance recesses 94 are provided in the portion 20 of the shaft 10. The clearance recesses 93 and 94 are so positioned on the respective parts, namely, ring 80 and portion 20 of shaft 10, as to permit the plane of the ring 80 to be rotated, for example, to the position shown in Figs. 1 and 5 wherein said plane is approximately only 5° out of parallelism with the axis of the shaft 10. Omission of such recesses 93 and 94 would cause engagement of the outer curved surface 81 of the ring 80 with portions 20 of the shaft 10 which would prevent such small relatively angular disposition between the central plane of ring 80 and the axis of shaft 10 and thus preclude the drawing of ellipses having comparatively small axes. However, with the recesses 93, 94 ellipses may be drawn to approximately a 5° angle of projection.

A coupling means acting as an amplifier is provided to guide the movement of the marker support 72 in response to movements of the bar 60 as controlled by movement of cam follower bar 56 on the curved surface 81 of ring 80, the said bar 56 being biased into contact with ring 80 by springs 36 and 49. This coupling means includes a slider 95 movable freely but with a close fit on the bar 60 and a second slider 96 movable freely but with a close fit on the main shaft 10 below the collar-like member 45. A pair of spaced projections 97 extend laterally from slider 95 toward the shaft 10 at diametrically opposite sides thereof. A pair of levers or linkage members 98 are pivoted by pinions 99, one to each of the projections 97. The common axis of the pinions 99 is offset on projections 97 relative to the axis of bar 60 so that its mid-point is intersected exactly by the projection vertically of a point *x* on the circle defining the locus of the center of the curved surface 81 of ring 80, this point *x* lying in the cross sectional plane of the ring 80 determined by the point *y* of contact of bar 56 with the curved surface 81 of ring 80. Thus the center point *z* of the common axis of pinions 99 traces out exactly the elliptical projection of the circle defining the locus of centers of the curved surface 81 of ring 80. The levers or linkages 98 are pivoted by pinions 100 to appropriate wings 101 provided on the marker or scribe support 72. Each lever or linkage member 98 has a longitudinal slot 102.

A pair of headed reference pinions 104 rotatively secure pivot blocks 105 to diametrically opposite points of the slider 96. The mid-point *w* of the common axis of the two reference pinions 104 is positioned to be intersected by the vertical axis of shaft 10. This point *w* of intersection is an essential feature in order that the scribe or marker 76 trace out a true ellipse in the use of the instrument as will be described. The concentric heads 106 of pinions 104 fit slidably in the respective slots 102 of the linkage members or levers 98. Set screws 107 that may be tightened or loosened in threaded holes 108 provided in the respective pivot blocks 105 extend through the respective slots 102 and with the clamp plates 109 facilitate longitudinal adjustment to desired positions of the linkages or levers 98 relative to the common axis of headed reference pinions 104.

Calibrations 110 are provided on the surface of levers 98 and serve as references for longitudinal adjustment of these levers 98 to desired positions for purposes of varying the major axes of ellipses to be drawn by the marker 76.

The socket 74 of the scribe support 72 is so positioned that the projection of the point of the scribe or marker 76 supported therein will lie exactly vertically under the center point *v* of the common axis of the pinions 100. Thus the point of the scribe or marker 76 will trace out in amplified form depending upon the adjustment of levers 98 relative to reference pinions 104, the true ellipse traced out as described by the point *z* on the common axis of pinions 99.

Operation of the device is as follows. The knurled collar 90 is loosened and the ring 80 is tilted so that its central plane makes a desired angle relative to the axis of the main shaft 10. The extent of tilt determines the angle of projection of the ellipse and the minor axis of the ellipse to be traced out by point *z*. Collar 90 is then tightened to retain the ring 80 in its tilted adjusted position. The levers 98 are then adjusted to desired positions relative to the common axis of reference pinions 104 by first loosening set screws 107 and sliding said levers until the calibrations 110 indicate the desired positions of the heads 106 of reference pinions 104 in slots 102 and then retightening the set screws 107. This adjustment determines the desired major axis of the ellipse to be drawn by marker 76.

Point 17 at the bottom of main shaft 10 is then positioned on the drawing surface 18 at the desired location and main shaft 10 is held substantially vertical by grasping of the knob 11 at its upper end. Then, while holding knob 11 firmly to prevent rotation of main shaft 10, knob 28 is grasped by the operator's other hand and rotated around the stationary axis of main shaft 10. This rotation acts to rotate the frame-like part 40 around the same axis and also collar-like parts 21 and 45 and the elements attached thereto or operating therein. In such rotation, the biasing action of the springs 36 and 49 acts to maintain the cam follower bar 56 in contact with the curved surface 81 of the tilted ring 80. Bar 60 moves in unison with cam bar 56.

Since the curved surface 81 is circular, the contact point *y* between cam follower bar 56 and this surface 81 as the bar is moved around the ring 80 is such that the vertical projection of this contact point traces out a locus of points always equidistant from and everywhere perpendicularly larger by the radius of the generating circle of the curved surface 81 than the ellipse formed by a perpendicular projection of the circle defining the locus of the centers of generation of circular surface 81. However, since the point *z* of the common axis of pinions 99 is offset as described to underlie the vertical projection of points *x* on the said generating circle, a true ellipse also is traced out by the center point *z* of the common axis of pinions 99 of linkages or levers 98. This ellipse is exactly the vertical projection of the circle defining the locus of centers of surface 81 of ring 80. Since the center point *w* of the common axis of the reference pinions 104 intersects the vertical axis of shaft 10, and since the point of marker 76 is vertically aligned with the center point *v* of the common axis of the pinions 100, the marker point moves in unison with point *v* and traces out an exactly similar ellipse of amplified magnitude, however, relative to that traced out by the center point *z*.

and draws the desired ellipse on the drawing surface 18. The simplicity of operation is obvious.

The recesses 93, 94 permit angular adjustment of the center plane of ring 80 to within approximately 5° of parallelism with the axis of shaft 10 and thus permits tracing out, if desired, of extremely narrow ellipses, that is, ellipses drawn to approximately a 5° angle of projection.

The horizontally disposed guide rods 31 and 48 to which the cam follower bar supporting parts 40 and 41 are secured under biasing action of springs 36 and 49 limit movement of the said bar 56 and also the bar 60 to horizontal to and fro motions toward and away from the axis of the main shaft 10 so that when the knob 28 is rotated around said axis as a center these bars 56 and 60 describe or generate cylindroidal surfaces having a perpendicular elliptical cross section which is the vertical projection of the circle defining the locus of centers of the curved surface 81 of the tilted ring 80 and the point *z* then traces out this elliptical cross section while point *v* and the point of scriber 16 trace out the same elliptical cross section amplified, however, by linkages or levers 98 to an extent determined by the setting of the linkages or levers relative to the heads 106 of the reference pinions 104, the point 16 drawing this as the desired ellipse on the drawing surface 18.

The structure described thus provides a comparatively simple arrangement for quickly drawing true ellipses of desired major and minor axes and narrow or large angles of projection at desired points on a drawing surface, eliminating the need for templates and enabling a user to fit the instrument to the work, rather than requiring the fitting of the work to the instrument.

While a specific embodiment of the invention has been disclosed, variations in structural detail within the scope of the claims are possible and are contemplated. There is no intention, therefore, of limitation to the exact details shown and described.

What is claimed is:

1. A drawing instrument of the character described comprising a main shaft, a ring having a circular outer surface and whose central plane is angularly adjustable relative to the axis of said shaft, a cam follower rod movable over the outer surface of said ring, supporting members rotatably carried on said main shaft, guide rods movable in said supporting members radially of said main shaft, members fixed to said guide rods, said cam follower rod being secured to said last-named members with its axis in parallelism with said main shaft axis, spring-biasing means for maintaining surface contact between said follower rod and the outer surface of said ring, a bar extending in parallelism with said cam follower rod and secured to one of said two last-named members, a marker support, supporting means rotatively carried on said main shaft and having a slot therein engaged by an end of said bar, a guide rod movable in said last-named supporting means radially of said main shaft and secured to said marker support, a marker carried by said marker support, a slider member movable over said bar, a slider member movable over said main shaft, linkage levers pivotally secured at opposite ends respectively to said first-named slider member and to said marker support and having longitudinally extending slots, reference pivots secured to said second-named slider member and slidable in said slots of said linkage levers, and adjusting means to fix the locations of said

reference pivots at desired positions in said slots.

2. In a device as per claim 1 in which the pivotal support of said linkage levers to said first-named slider member is on a horizontal axis that is intersected at its midpoint by a vertical projection of the locus of centers generating the curved surface of the ring in a plane perpendicular to the point of contact of the cam follower rod with the circular surface of the ring, and in which the pivotal support of said linkage levers to said marker support is on a horizontal axis that is intersected at its midpoint by a vertical upward projection of the point of the marker, and in which the reference pivots are on a common horizontal axis that is intersected at its midpoint by the main shaft axis.

3. A device as per claim 1 in which said spring-biasing means are mounted on said first-named guide rods.

20 4. A device as per claim 1 including manipulating means secured to one of said first-named supporting members for moving said cam follower rod over the outer surface of said ring, said manipulating means including an arm secured to said one of said supporting members and slidably in one of the members fixed to one of said guide rods.

5. A drawing instrument of the character described comprising a main shaft, a ring having circular curved contour in its outer surface, adjustable means for securing said ring to said shaft for angular adjustment of the central plane of the ring about an axis transverse to the axis of the shaft and with the center of the ring intersecting the shaft axis, said shaft and said ring having recesses disposed to permit said plane to be adjusted to make relatively small angles between it and the shaft axis, tightening means for fixing said ring in adjusted positions, a cam follower bar movable over the curved outer surface of said ring, supporting means for maintaining the axis of said bar in parallelism with the axis of said main shaft, carrying means for said supporting means rotatable about said main shaft, a rod attached to said supporting means with its axis parallel with that of said bar, a slider movable on said rod, levers, pivots securing said slider to said levers, the mid-point of the pivot axes being disposed to be intersected by the vertical projection of the locus of centers generating the circular surface of the ring in a plane at right angles to the central plane of the ring and including the contact point between the ring surface and the cam follower bar, a second slider movable over said main shaft, reference pivots secured to said second slider and having a common axis intersected at its mid-point by the main shaft axis, said reference pivots engaging in slots in said levers, a marker, a marker support, carrying means for said marker support rotatably mounted on said shaft, said support being movable in radial directions on said carrying means toward and away from said main shaft axis, said rod slidably engaging a portion of said last-named carrying means and pivots having a common horizontally disposed axis securing said levers to said marker support, said last-named common axis being bisected by the vertical projection of the point of the marker carried by said marker support.

6. A drawing instrument of the character described comprising a main shaft, a ring, a stub shaft secured to said ring and extending in a diametrical direction thereof into an opening provided in said main shaft, a second stub shaft

adjustably secured to said ring at a diametrically opposite point thereof from said first-named stub shaft with its axis alined with the axis of the first stub shaft, said first-named stub shaft having a threaded portion, a coupling sleeve having a threaded portion to threadedly engage said first-named threaded portion and also having a socket alined with the alined axes of the two stub shafts to receive said second stub shaft, said sleeve being capable of being tightened on the threaded portion of said first-named stub shaft against a surface of said main shaft to maintain said ring in adjusted angular positions on said main shaft, said opening in said main shaft being positioned so that the alined axes of the two stub shafts intersect the axis of said main shaft, a follower movable over the surface of said ring, a marker, a marker support and coupling means connecting said marker with said follower.

7. A device as per claim 6 in which said coupling means includes amplifier levers pivotally secured to said marker and to a portion of said follower.

8. A device as per claim 6 in which said ring has a circularly curved outer surface and in which said ring and said main shaft have recesses to permit positioning of the central plane of the ring to small angles relative to the axis of the main shaft.
